UNITED STATES PATENT OFFICE.

CHARLES ROSSOW, OF CHICAGO, ILLINOIS.

IMPROVEMENT IN SOFA-BEDSTEADS.

Specification forming part of Letters Patent No. **138,819**, dated May 13, 1873; application filed January 31, 1873.

To all whom it may concern:

Be it known that I, CHARLES Rossow, of the city of Chicago, county of Cook and State of Illinois, have invented a new and useful Improvement in Folding Lounges; and I hereby declare that the following is a full, clear, and exact description of the construction and operation of the same, reference being had to the annexed drawing making a part of this specification, in which—

Figure 1 is a perspective view of the lounge closed or folded; Fig. 2, a view of the lounge opened, to be used as a bed; Fig. 3, a detailed view of the pillow, with attachments for securing its position when in use, and otherwise; Fig. 4, a front elevation of the end of the lounge opened, showing the improvement in securing the legs in a closed position.

Fig. 1 shows, at B B, the pillow stowed away beneath the elevated portion of the lounge m. This is done by slipping the wire pins w w, visible in Fig. 3, into two corresponding openings at the bottom of and on the exterior of the elevation m.

Fig. 2 shows the lounge opened, the pillow B fastened with the hook C to the lounge on the top, while the pins w w are inserted into corresponding openings in the lounge, while

the jointed brace a a, dropping on the pin x, gives stability to the pillow.

Fig. 2 shows, at d d, the sheet-iron legs in use, supporting the opened part T of the lounge, which, when closed, is the top or seat of the lounge, as shown in Fig. 1. f f are the springs, holding the legs d in position to prevent movements sidewise, as is the case in ordinary lounges. g is a loop for lifting up the top T.

Fig. 3 shows the pillow B, the pins w and hook C for fastening the same in position, as also the jointed brace a a for keeping the pillow in position.

Fig. 4 shows the legs d when not in use, held up by the springs f, as also the recess E, into which they drop, and in which they are held firmly by the springs f when in use.

What I claim as of my invention, and desire to secure by Letters Patent, is—

In combination with the stationary head m and hinged part T, the detachable pillow B, the jointed brace a a, the pins w w, and hook C, arranged in the manner and for the purpose set forth.

CHARLES ROSSOW.
